UNITED STATES PATENT OFFICE.

MARTIN A. HOWELL, JR., OF OTTAWA, ILLINOIS.

IMPROVEMENT IN CORN-PLANTERS.

Specification forming part of Letters Patent No. 27,807, dated April 10, 1860.

To all whom it may concern:

Be it known that I, M. A. HOWELL, Jr., of Ottawa, in the county of La Salle and State of Illinois, have invented a new and Improved Corn-Planter, and I do hereby declare that the following is a full, clear, and exact description of the same, reference being had to the annexed drawings, making a part of this specification, in which—

Figure 1 is a side sectional view of my invention, taken in the line $\alpha\alpha$, Fig. 2; Fig. 2, a plan or top view of the same; Fig. 3, a front elevation of the same; Fig. 4, a detached edge view of one of the rollers or wheels of the same, showing their operation as coverers.

Similar letters of reference indicate corresponding parts in the several figures.

This invention relates to a novel seed-dropping device whereby the seed may be dropped evenly or uniformly and without the liability of the device used for the purpose becoming choked or clogged, the device also working with but little friction and without the liability of being deranged by use or its perfect operation affected by wear and tear.

To enable those skilled in the art to fully understand and construct my invention, I will proceed to describe it.

A represents a rectangular frame, the front part of which is supported by two curved runners, B B, shod at their outer sides with metal plates $a\alpha$, which project down a short distance below the outer sides of the runners. The runners have an inclined lower surface, as shown clearly in Fig. 3, and they consequently make furrows b , to receive the seed, with inclined bottoms, as shown clearly in Fig. 4. The back part of the frame A is supported by wheels or rollers C C, the peripheries of which are inclined, corresponding with or approximating to the forms of the bottoms of the runners B, as shown clearly in Fig. 3. The peripheries of the wheels or rollers C C are somewhat wider than the runners B B, the runners and wheels being in line with each other. This is also shown in Fig. 3.

On the front part of the frame A there are placed two seed-boxes, D D, one near each side of the frame, as shown in Fig. 2, and in each seed-box there is placed a seed-cup, E, said cup being attached to a shaft, F, which passes through the upper parts of the boxes D D, and has its bearings therein, as shown at c , Fig. 2.

The seed-cups E may be of semi-cylindrical or an approximate form, having each a cap or cover, d , at each end of its top, leaving an opening, e , at the center to allow the cups to be supplied with seed. At each end of the cup and near their upper ends an opening, f , is made through projections g to form seed-cells. The object of the projections is to form cells f of sufficient capacity to contain the requisite quantity of seed. (See Fig. 1.) The cells f have a tangential position relatively with the shaft F, so as to admit of the ready discharge of the seed when said cells are brought in the proper position to discharge the seed. Each cell f is covered by a flap or valve, h , which is attached to the outer side of the cup, as shown clearly in Fig. 3.

Within each seed-box D there is placed a vertical slide, G. These slides G are fitted in slots i in the bottoms of the boxes D, and serve as cut-offs, as will be presently shown. These slides are actuated by the movement of the seed-cups E through the medium of projections j , attached to them. Across the upper ends of the seed-boxes D D traverse-bars k are placed—one at the front and the other at the back part of each box.

The operation is as follows: The seed to be planted is placed in the seed-cups E E, and as the machine is drawn along the shaft F has a rocking motion given it by means of a rod, $a\alpha$, and arm $b\alpha$, the arm $b\alpha$ being attached to the shaft F, and the rod $a\alpha$ actuated by an attendant or actuated automatically by any suitable mechanism. By this rocking movement of shaft F the seed-cups E are subjected to a similar movement, and the seed-cells f of the cups E alternately filled with seed, the cells filling as they pass down and ascending in a filled state, the seed being discharged from them as they reach their culminating-point in consequence of the flaps or valves h being opened by coming in contact with the traverse-bars k , the seed falling from the cells f by its own gravity and into the seed-boxes D. The movement of the slides G, which are actuated by the projections j of the cups E, is such that the part of the seed-boxes into which the seed is dropped is closed by said slides and retained until the slide is moved to close the opposite sides to retain or hold the seed dropped at the other ends of cups. By this arrangement the seed has two discharges before being deposited in the fur-

rows—to wit, one from the cells *f* and the other from the boxes *D*, the latter being near the surface of the earth and insuring the proper disposition of the seed in the furrows. This seed-dropping arrangement is not liable to become choked or clogged, and works with but little friction. The seed is covered by the wheels or rollers *C*, their prominent or larger edges or sides slicing the earth off from one side of the furrows *b*, and having a tendency while covering the seed to force it upward, so as to insure its being planted at a uniform depth. This will be understood by referring to Fig. 4, in which the position of the seed as dropped is shown by solid red lines, and the position given it by the wheels or rollers in covering is shown by red dotted lines.

I do not confine myself to the flaps or valves *h* for the purpose of retaining the seed in their

cells *f* until the proper time of discharge for various equivalent devices may be used.

Having thus described my invention, what I claim as new, and desire to secure by Letters Patent, is—

1. The employment or use of rocking seed-cups *E E*, placed within or above the seed-boxes *D D*, and provided with seed-cells *f* and flaps or valves *h*, or their equivalents, to operate as and for the purpose set forth.
2. In combination with the rocking seed-cups *E E* and seed-boxes *D D*, the slides or cut-offs *G*, operated from the rocking cups *E*, substantially as and for the purpose set forth.

MARTIN A. HOWELL, JR.
